2 SHEETS—SHEET 2.

UNITED STATES PATENT OFFICE.

FANNIE FINLEY, OF CHAFFEE, MISSOURI.

PATIENT'S TRANSPORTING AND TREATING APPARATUS.

1,270,136.

Specification of Letters Patent. Patented June 18, 1918.

Application filed March 1, 1917. Serial No. 151,829.

To all whom it may concern:

Be it known that I, FANNIE FINLEY, a citizen of the United States, residing at Chaffee, in the county of Scott and State of Missouri, have invented certain new and useful Improvements in Patients' Transporting and Treating Apparatus; and I do hereby declare the following to be a full, clear, and exact description of the invention, such as

10 will enable others skilled in the art to which it appertains to make and use the same.

This invention relates to improvements in apparatus which is especially adapted for use in hospitals or the like for moving patients from their beds to the operating room and is especially adapted for the moving of patients having fractures and is equipped with the novel means whereby the movement of the patient will be accomplished in an

20 efficient and reliable manner.

A still further object of this invention is the provision of an apparatus which is mounted upon wheels and is so constructed that the same may be readily pushed to surround the bed and equipped with the novel means whereby a patient may be lifted from the bed in a quick, reliable and efficient manner.

A still further object of this invention is

30 the provision of an apparatus of this character, which is especially adapted for use in hospitals or the like and is equipped with rollers, which support pads, which pads are secured to auxiliary sectional pads which

35 are adapted to be placed under the patient and the rollers are associated with shafts which are driven by chains which may be operated by a single person for raising the patient upon the auxiliary pads, thus plac-

40 ing the patient in such a position that he may be moved from his bed into an operating room and may be moved away from the bed so that the same may be changed and thoroughly aired.

45 A still further object of this invention is the provision of an apparatus of this character, which is supported upon wheels so that a person may move a patient from his bed and so handle the patient as to obviate

50 any fear of the patient being further injured during the movement thereof.

A still further object of this invention is the provision of an apparatus of this character, which will be simple, practical, and

55 comparatively inexpensive in construction

and one that can be manufactured and sold at a low cost.

With these and other objects in view as will become more apparent as the description proceeds, the invention consists in the

60

novel combination and arrangement of parts as will be hereinafter more fully described and set forth in the claims hereto appended.

In the drawings:

Figure 1 is a perspective view of the apparatus as made in accordance with this invention,

Fig. 2 is an end elevation illustrating the operating mechanism,

Fig. 3 is a fragmentary transverse sectional view,

Fig. 4 is a detail sectional view,

Fig. 5 is a detail sectional view of one corner of the post of the bed, illustrating the journaling of the operating shaft thereto,

75

Fig. 6 is another detail sectional view illustrating the manner in which the device is supported and held against movement during the transporting of the patient.

Like numerals of reference designate cor-

80

responding parts in all the figures of the drawings.

Referring more particularly to the drawings, the numeral 1 designates the corner posts which are provided in their lower ends with suitable rollers 2, the upper ends of the corner posts have secured thereto the side bars 3 and end bars 4. The end bars 4 are made in sections to telescope one within the other and are held at various adjusted positions by a set screw 5, thus it can be seen that the corner posts may be varied toward or away from one another.

The corner posts 1 are provided adjacent their lower ends with the telescoping bars

85

6, which are held in adjusted position by a set screw 7.

A side bar 8 is formed integrally with the corner post 1 adjacent the lower end thereof and is formed integrally with the corner

100

post 1 at the point of juncture of the end bars 6 therewith.

A second side bar 8' is hingedly secured as at 9 to one corner post 1 and has its opposite end removably secured therein by a

105

hook 10 which is adapted to engage an apertured plate 11 carried by one corner post 1 adjacent the lower end thereof, thus permitting the side bar 8' to be raised upwardly and permit the four corner posts

110

to surround a bed of the ordinary type, the purpose of which will be hereinafter more fully described.

Each of the corner posts 1 is provided adjacent its upper ends with a laterally extending bearing bracket, 12, in which is journaled a longitudinally extending shaft 13, which shafts are arranged on opposite sides of the bed and parallel with the side bars 3.

The shafts 13 extend outwardly beyond one end of the bed as at 14 and have secured on their extended ends sprocket wheels 15. One lower end bar 6 has secured to one section adjacent the inner end thereof a stub shaft 16 on which is secured a pair of sprocket wheels 17 which are adapted to have trained thereover the chains 18 and 19. The chain 18 is also trained over one of the sprocket wheels 15 on one end of one of the shafts 13. The chain 19 is trained over the other sprocket wheel 15 on the other side shaft 13 on the opposite side of the frame.

A crank handle 19' is secured to the outer sprocket wheel 17, thus facilitating the rotation of the sprocket wheels 17, rotating the chains 18 and 19 and in turn turning the sprocket wheels 15 and shafts 13, the purpose of which will be hereinafter more fully described.

A plurality of rollers 20 are arranged in pairs and each pair is journaled upon each of the shafts 13. One roller of each pair is journaled near each end of the side bars, as shown in Fig. 1 of the drawings.

A plurality of flexible strips 21 formed of any suitable flexible material have one end secured to the shafts 13 as at 22, and their opposite ends trained over the rollers 20, the lower ends of the strips 21 provided with suitable snap hooks 23.

A plurality of substantially inverted V-shaped strips 24 have their apexes secured to one face of the strips 21 adjacent the lower ends thereof, thus positioning the leg portions 25 on opposite sides of the strips 21 and their lower edges flush with the lower edge of the strips 21 and provided with openings, in which are secured suitable snap hooks 26, the purpose of which will be hereinafter more fully described.

A plurality of supporting strips 27 are formed of suitable fabric material, such as canvas, leather or the like, and are substantially rectangular in cross section, each strip 27 is provided in its upper edge with openings 28, which are adapted to receive the snap hooks 23 and 26 of the strips 21 and 24, as shown in Fig. 1 of the drawings. The connecting of the supporting strips 27 to the strips 21 and 24 position the side strips inside of the frame. The supporting strips 27 are provided in their lower edges with a plurality of relatively spaced open-

ings 29 and each of the strips 27 have their side edges covered by suitable flexible elements, such as tin, metal or the like, and designated 30, thus protecting the strips from pulling out when in use.

A plurality of substantially rectangular pads or bands 31 are provided in their side edges with openings, which are adapted to receive suitable fasteners 32, such as links or the like, which connect the bands to each other as shown in Fig. 1, and the ends of the bands are provided with snap hooks 32', which are adapted to be removably secured in the openings 29 in the lower edges of the side supporting strips 27, thus connecting the bands 31 to the lower edges of the side strips 27, as shown in Figs. 1 and 3 of the drawings.

A plurality of elongated strips 33 are secured by one end to the top bar 4 remote from the top bar 4 from which the sprocket wheels extend and these strips have one of their ends secured to the top bar 4 as at 34 and have their lower ends depending therefrom. The strips 33 are arranged in spaced relation and have secured in their lower ends centrally of their side longitudinal edges, the snap hooks 35, which are adapted to engage the end strips 31 at one side edge thereof to hold the strips or bands 31 and side strips 27 horizontally aligned during the lifting operation.

A strip 36 has one end attached to the end bar 6, and a plurality of similar strips 36, arranged in spaced relation, have one end 104 of each, as at 37, attached to the side bars 8'. Each of these strips 36 is provided on its free end with suitable elastic or any other suitable flexible material, in which is secured a snap hook 39, which hook is adapted to engage the edge of one of the intermediate bands 31, as shown in Fig. 1 of the drawings.

The hooks 39 being secured in the elastic portion 38 of the bands 36 permit the same 110 to be drawn taut and connected to the bands 31 and serve to hold the bands against lateral movement during the lifting of the bands 31.

In operation, the apparatus is assembled 115 as described. In positioning the device for use, the side bar 8' is lifted upwardly on its hinge 9, the device is pushed around the bed and the side bar 8' is dropped downwardly again and the device is in position 120 above the bed, the strips 36 and 33 are released from the bands 31, the bands 31 are then all released from one pair of the side supporting strips 27, the bands are then forced under the patient and connected to 125 the lower edges of the side supporting strips 27, the strips 33 and 36 are then connected to the bands 31 and a person grasps the crank 19 rotating the chains 18 and 19, rotating the sprockets 15 and shafts 13, 130

thus rotating the bands 21 over the rollers 20 and about the shafts 13 lifting the bands 31 upwardly and the patient may be transported to an operating room or elsewhere. 5 It being understood that the bands 33 and 36 hold the bands 31 carrying the patient against movement laterally or longitudinally during the moving action. It is also to be understood that the rollers 2 permit 10 the apparatus to be readily transported from one room to another, as previously described.

What is claimed is:

1. A device of the class described comprising a support including side and end bars, posts connecting the side and end bars, shafts journaled to the posts, sprocket wheels carried by one end of each of the shafts, means for rotating the shafts and 20 wheels, a plurality of bands removably connected together constituting a support, strips secured to the shafts, supporting strips removably connected to the ends of the bands and to the first named strips, 25 whereby upon the rotation of the shafts the bands will be raised and lowered, and means connected to the support and to the bands for holding the same against swinging movement during the raising and lowering 30 movements.

2. A device of the class described comprising a frame including spaced corner posts, side and end bars connected to the upper ends of the corner posts, said end bars being adjustably mounted on one another, shafts journaled to the end posts and arranged parallel to the side bars, sprocket wheels carried by one end of the shafts, a 35 plurality of bands, means for removably

connecting the bands together to form a support, supporting strips, means for removably connecting the supporting strips to the ends of the bands, connecting strips, the ends of the connecting strips being secured to the shafts and their free ends being 40 connected to the upper edges of the supporting strips, and means trained over the sprocket wheels of the shafts to rotate the shafts for moving connecting strips for raising and lowering the bands, and means for holding 45 the bands against swinging movement during the lifting and lowering action.

3. A device of the class described including a supporting structure having corner posts, side bars secured to the corner posts, 55 said side bars being movable to permit the supporting structure to be placed around a bed, shafts journaled to the corner posts, means carried by the shafts through the medium of which the shafts may be rotated, a 60 plurality of bands, means for connecting the bands together, supporting strips removably connected to the ends of the bands, connecting strips removably secured to the upper edges of the supporting strips and to the 65 shafts, whereby upon rotation of the shafts the bands will be lifted vertically with relation to the supporting structure, and means secured to the supporting structure and to the bands for holding the bands against 70 swinging movement during the lifting or lowering action.

In testimony whereof I affix my signature in presence of two witnesses.
